C. T. WESTLAKE,
DRAW BAR CONNECTION,
APPLICATION FILED JUNE 30, 1915.

1,212,719.

Patented Jan. 16, 1917.

Inventor
Charles T. Westlake
By *J. T. Edwards, Atty.*

UNITED STATES PATENT OFFICE.

CHARLES T. WESTLAKE, OF ST. LOUIS, MISSOURI, ASSIGNOR TO TRANSOM DRAFT GEAR COMPANY, OF ST. LOUIS, MISSOURI, A CORPORATION OF DELAWARE.

DRAW-BAR CONNECTION.

1,212,719.

Specification of Letters Patent. Patented Jan. 16, 1917.

Original application filed March 1, 1915, Serial No. 11,360. Divided and this application filed June 30, 1915. Serial No. 37,199.

To all whom it may concern:

Be it known that I, CHARLES T. WESTLAKE, a citizen of the United States, residing at St. Louis, Missouri, have invented a certain new and useful Improvement in Draw-Bar Connections, of which the following is a full, clear, and exact description, such as will enable others skilled in the art to which it appertains to make and use the same, reference being had to the accompanying drawings, forming part of this specification.

My invention relates generally to the draw-bars of railway cars and more particularly to the connection between the rear end of the coupler shank and the forward end of the draw-bar extension, the principal object of my invention being to generally improve upon and simplify the present forms of connections of the character to which my invention relates, and to provide a connection which will permit the interengaging parts to be easily and quickly assembled or taken apart.

A further object of my invention is to provide a connection which involves the use of a minimum number of parts and which wholly eliminates projections from the sides of the draw-bar shank or draw-bar extension, thus providing greater clearance for the united parts during their lateral swinging movement.

This application is a division of a copending application filed by me March 1, 1915, Serial No. 11,360.

With the foregoing and other objects in view, my invention consists in certain novel features of construction and arrangement of parts, hereinafter more fully described, claimed and illustrated in the accompanying drawings, in which—

Figure 1 is a plan view of a coupler shank and draw-bar extension connected by my improved means. Fig. 2 is a sectional view taken approximately on the line 2—2 of Fig. 1. Fig. 3 is a horizontal section taken approximately on the line 3—3 of Fig. 2. Fig. 4 is a perspective view of the forward end of a draw-bar extension, the same being constructed in accordance with my invention. Fig. 5 is a perspective view of the key utilized in my improved connection.

Referring by numerals to the accompanying drawings, 10 designates a draw-bar extension, the main body portion of which may

be of any desired shape, though preferably an elongated hollow member and substantially square in cross section.

Formed in the forward end of this extension is a pocket 11, open in front, and at the top, and formed integral with the lower portions of the side walls 12 of this pocket is a bottom plate 13 provided at its front end with an upwardly projecting transversely disposed lip or flange 14.

Formed through the central portions of the side walls 12 are key slots or openings 15. The rear end of the coupler shank 16 is formed so as to fit snugly within the pocket 11, the top of the rear portion of said shank being preferably flush with the top surface of the extension 10, and formed on the underside of said shank is a transversely disposed shoulder 17 which, when the parts are assembled, bears directly against the rear side of lip or flange 14.

Formed through the side walls of the rear portion of the coupler shank are key slots or openings 18, which, when the parts are assembled, coincide with the openings 15 and seated in said coinciding openings are the end portions of a transversely disposed key 19, the end faces of which are preferably flush with the outer faces of the walls 12. Formed in both edges of this key 19 are centrally arranged notches 20, and when the parts are properly assembled, a bolt 21 is inserted through suitably located bolt holes in the top and bottom walls of the coupler shank and the bottom wall 13, said bolt when so positioned, being seated in the rear one of the notches 20. Thus, the key 19 and bolt 21 serve to rigidly connect the coupler shank to the draw-bar extension, and by virtue of the interengagement between said bolt and key, the latter is held against lateral displacement. Such construction provides a comparatively simple connection which permits the parts to be readily assembled or taken apart and provides for the direct transmission of all pulling and buffing strains directly from one part to the other.

Ordinarily, the key utilized for connecting the coupler shank to the draw-bar extension is formed with a projection or head on one end, the same occupying considerable space and the other end projecting a sufficient distance beyond the opposite wall to

receive a cotter or like device for preventing displacement. These projecting ends of the key occupy considerable space and prevent the requisite sidewise movement of the forward portion of the draw-bar extension within the available space between the center sills or draft sills of the car.

In my improved construction, the key does not project beyond the side walls of the draw-bar extension, and thus the forward portion of said extension and the coupler head associated therewith have a comparatively greater latitude of transverse movement.

While I have shown and described my improved connection as being applicable between a coupler shank and draw-bar extension, it is obvious that practically the same construction could be used between the rear end of the draw-bar extension or the elongated shank of a coupler and the forward end of a draft gear yoke.

Minor changes in the size, form and construction of the various parts of my improved device can be made and substituted for those herein shown and described, without departing from the spirit of my invention, the scope of which is set forth in the appended claims.

I claim:

1. In a connection of the class described, a draw bar extension provided at its outer end with a pocket which is open front and top, a coupler shank, the rear end of which fits snugly within said pocket and is movable into and out of the same by a relative vertical movement between the two parts, and interlocking means for rigidly securing the parts to each other, which interlocking means comprises a transversely disposed member which passes through the coupler shank and through the walls to the sides of the pocket in the draw bar extension, and a vertically disposed member which

passes through the coupler shank and 45 through the wall below the pocket in said draw bar extension.

2. In a connection of the class described, a draw bar extension, a pair of vertically disposed side walls integral with the outer 50 end of said extension, a bottom plate connecting the lower portions of said walls, which walls and bottom plate form a pocket open at front and top, a coupler shank the rear end of which fits snugly within said 55 pocket, a transversely disposed key seated in the rear end of the coupler shank and in the walls to the sides of the pocket, and a vertically disposed member passing through the rear portion of the coupler 60 shank and through the bottom plate, which vertically disposed member engages the key to lock the same against withdrawal.

3. In a connection of the class described, a draw bar extension, a pair of vertically 65 disposed side walls integral with the outer end of said extension, a bottom plate connecting the lower portions of said walls, which walls and bottom plate form a pocket open at front and top, a coupler shank the 70 rear end of which fits snugly within said pocket, a transversely disposed key seated in the rear end of the coupler shank and in the walls to the sides of the pocket, the ends of which key are flush with the outer faces 75 of said side walls, and a vertically disposed member passing through the rear portion of the coupler shank and through the bottom plate, which vertically disposed member engages the key to lock the same against 80 withdrawal.

In testimony whereof I hereunto affix my signature in the presence of two witnesses, this 16th day of June, 1915.

CHARLES T. WESTLAKE.
